UNITED STATES PATENT OFFICE.

EVERETT R. JONES, OF WYANDOTTE, MICHIGAN, ASSIGNOR OF ONE-HALF TO CARL BEUTHIEN, OF DETROIT, MICHIGAN.

CALK.

Application filed January 28, 1926. Serial No. 84,398.

This invention relates to calks for horseshoes, one of the objects being to provide a calk adapted to be attached readily to a horseshoe and which can be readily adjusted or shaped so as to become accurately seated within apertures already provided within the shoe for the reception of the calks.

A further object is to provide a calk which has means for reinforcing its connections with the shoe, said means also constituting a stop lug or ear for engagement with the hoof to which the shoe is applied.

A further object is to provide a calk which can be elongated or shortened as desired in order to bring portions thereof into proper position for insertion into apertures provided therefor within the shoe.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Fig. 1 is a side elevation of a horseshoe having the present improvements combined therewith,

Fig. 2 is a bottom plan view thereof,

Fig. 3 is a top plan view of one of the calks,

Fig. 4 is an inner elevation thereof, and

Fig. 5 is a section on line 5—5 Fig. 4.

Referring to the figures by characters of reference, 1 designates a plate of malleable iron or other suitable material provided with an intermediate ear 2 of such length that, when the calk is applied to the bottom surface of a horseshoe S, the upper portion of this ear will project above the horseshoe, as shown particularly in Fig. 1, so as to provide a stop ear against which the hoof to which the shoe is applied can thrust. The end portions of the plate, extending from the sides of the ear 2 are curved inwardly beyond one face of the ear so as to extend under and constitute supports for

the shoe S. These end portions constitute wings the terminals of which are curled inwardly as shown at 3 so as to provide upwardly extending tapered lugs 4 which are split longitudinally. The free longitudinal edge of each of these terminals is preferably reduced in thickness, as shown at 5. Thus as the tapered curled portions are reduced at their free longitudinal edges and these reduced portions lap the adjacent portions of the terminals, it will be apparent that when any one of the tapered portions is inserted into an opening O in the shoe and driven thereinto, the said tapered portion will contract so as to fit snugly against the wall of the opening.

In preparing the shoe S to receive the calks, openings O are formed therein, the same being disposed in pairs at the sides and forward portion of the shoe. One calk is used in connection with each pair of openings. The plate 1 is arcuate from side to side or end to end and by bending the same with a hammer or the like the tapered portions 4 can be properly positioned relative to each other so that both of them can be simultaneously inserted into the respective openings of one pair. The said tapered portions are then driven forcibly into the openings and, as before explained, will contact in order to fit snugly against the walls of the openings. When the tapered portions have been driven home the plate 1 will rest against the bottom surface of the shoe while the ear 2 will extend above the shoe as already explained and as illustrated in Fig. 1.

It will be seen that this device can be made cheaply of sheet metal and can be easily applied and removed as desired.

What is claimed is:

1. A calk for horseshoes including an arcuate plate, inwardly curled terminal portions extending from the plate and tapered to constitute attaching lugs, said lugs being contractible when forced into openings in a horseshoe, and an ear extending from an intermediate portion of the plate for engaging the outer edge of a horseshoe and projecting above the shoe to constitute hoof-engaging means.

2. The combination with a horseshoe having spaced openings extending therethrough, of a calk including an arcuate

plate, inwardly curled end portions on the plate constituting tapered lugs extending from the plate and insertable into the openings, said lugs being contractible when forced into the openings to bind upon the walls thereof, and an ear extending from the plate for engaging the edge of the shoe

and projecting thereabove for engagement with the hoof to which the shoe may be attached.

In testimony that I claim the foregoing as my own, I have hereto affixed my signature.

EVERETT R. JONES.
